United States Patent Office.

ALBERT C. BROWN, OF CHICAGO, ILLINOIS.

Letters Patent No. 80,591, dated August 4, 1868.

IMPROVED WEATHER-STRIP.

The Schedule referred to in these Letters Patent and making part of the same.

TO ALL WHOM IT MAY CONCERN:

Be it known that I, ALBERT C. BROWN, of Chicago, in the county of Cook, and State of Illinois, have invented a new and useful Improvement in Weather-Strips; and I do hereby declare and make known that the following is a full, clear, and exact description of the same, reference being had to the accompanying drawings, and the letters and figures marked thereon, which form part of this specification.

My invention relates to an improvement in the construction of rubber moulding to be used and applied upon doors and windows for the purpose of excluding cold, wind, dust, snow, and rain; and it consists in forming the rubber bearing-surface by folding the rubber strip, and inserting the edges of the same securely in suitable grooves in the moulding, thus presenting a rounded, firm, elastic bead for the bearing-surface against the door or window, and in combining, with the said rubber moulding, a concave stop or abutment to be applied upon the door or sash, so as to receive said elastic bead, and form a continuous contact between the rubber and its receiving-groove, instead of having simply a line of contact, as in the ordinary mode of applying weather-strips, thus much more perfectly attaining the object desired.

To enable those skilled in the art to manufacture and use my said invention, I will proceed to describe the same with particularity, making reference in so doing to the aforesaid drawings, in which—

Figure 1 represents a front view of my invention as applied to a door.

Figure 2 is a transverse section at the line *z* in fig. 1, and

Figure 3 is a cross-section of the threshold and its attachment.

Similar letters of reference in the several figures denote the same parts of my invention.

In applying my invention, the rubber moulding is applied or fastened to the stop or casing of the door or window, and the concave bed receiving the elastic bead is applied upon the door or the sash. When applied upon the bottom of doors, however, the moulding is made much heavier and is applied upon the door, while the concave grooved bed is secured upon the threshold, as clearly seen in the drawings.

A represents a door, and B the casing or stop, against which the margin of the door closes when shut. Upon the sides of the stop or casing, the moulding *b* is secured in such a manner that the rubber bead *a*, inserted therein, projects beyond the face of the stop, so that the bed *C* upon the door shall press against the bead when the door is closed, thus making a close joint all around the door, as clearly shown in fig. 2.

C represents a strip of wood extending around the door in such a position that the bead *a* of the moulding fits into the concave channel *c*, formed in the strip *C*, as clearly shown in the drawings, thus forming a tight joint, not at a single line around the door, but for the whole concave surface of the stop and convex surface of the bead.

It is obvious that such a joint as is produced by my invention will be far more effectual in excluding cold and dust and storms than the ordinary kind of weather-strips, where the contact between the moulding or rubber and the door is a line without width.

The rubber at the bottom of the door closes against the concave groove *c* in the strip *C* upon the door-sill *T*, producing the same result.

Having described the construction and operation of my invention, I will specify what I claim, and desire to secure by Letters Patent.

I claim the combination of the moulding *a b* with the stop *C*, provided with a groove, *c*, arranged substantially as and for the purposes specified.

ALBERT C. BROWN.
